UNITED STATES PATENT OFFICE.

ANTHONY J. BLIX, OF ANACONDA, MONTANA TERRITORY.

CARTRIDGE-BELT.

SPECIFICATION forming part of Letters Patent No. 404,677, dated June 4, 1889.

Application filed March 6, 1889. Serial No. 302,077. (No model.)

To all whom it may concern:

Be it known that I, ANTHONY J. BLIX, a citizen of the United States, and a resident of Anaconda, in the county of Deer Lodge and 5 Territory of Montana, have invented certain new and useful Improvements in Cartridge-Belts; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a perspective view of my improved cartridge-belt, showing one of its compartments or cartridge-holders open. Fig. 2 is a perspective view of one of the holders removed from the belt and showing it open. Fig. 3 is a similar view of the holder or compartment closed. Fig. 4 is a plan or top view of the holder, and Fig. 5 is a vertical transverse sectional view on line *x x* in Fig. 4.

Like letters of reference denote corresponding parts in all the figures.

25 My invention relates to cartridge-belts adapted to hold loaded shells or rifle or pistol cartridges, and has for its object to so hold the same that a given number may be detached from the belt and dropped into the 30 hand simultaneously without picking them out one by one from the pockets of an ordinary cartridge-belt.

To this end my invention consists in the combination, with a belt adapted to be carried 35 around the waist or across the shoulder, of a series of separate ammunition-holders, each containing a given number of cartridges, substantially as and for the purpose hereinafter more fully set forth.

40 Reference being had to the accompanying drawings, the letter A denotes a belt of leather or other suitable material, which is provided with a series of cartridge holders or carriers B, adapted to hold cartridges of any given 45 pattern and caliber. If, for example, the belt is intended for carrying the ammunition for a Colt's 44-caliber frontier revolver, then each holder or cartridge-carrier is chambered for six 44-caliber Winchester C. F. cartridges, 50 which is the number required to charge the cylinder of that particular arm. Each of these

holders consists of a back plate C, which is stamped or struck up by suitable dies to form recesses D of such size and shape that they will fit one longitudinal half of the particular 55 cartridge for which the holder is intended, and to the lower part of which a similarly chambered or recessed front plate E is hinged at *e e*, having recesses D' corresponding in size, shape, and position to the recesses D in 60 plate C, so that when the two parts or plates C and E are folded together, the registering-recesses D and D' will form chambers or compartments, each of which will fit and is adapted to receive a cartridge of the shape 65 and caliber for which the holder is intended to be used.

Between the folding plates C and E is located a spring guard or keeper F, the lower coiled ends *f f* of which are fastened in the 70 lower corners of plate C, while its upper end, which runs across the cartridge-recesses D D, is serrated to form keepers or guides *d* corresponding to and facing the recesses D' in plate E. In order to make room for the spring- 75 coils *f f*, plate E is cut out at its lower corners, as shown at *c c*, so that the spring-coils may project through these apertures when the plates are folded together. When so folded, the plates are held together by two spring- 80 catches G G, the hook-shaped ends *g g* of which engage notches *b* in the upper rim of plate C. (See Fig. 5.) These catches are released by a pair of short levers H, pivoted at *h h* on the front plate E and having their inner or meeting ends jointed together at *i*. These inner 85 ends are provided with buttons or thumb-pieces II, so that by depressing the same with a quick motion of the hand the outer ends of the levers will bear against the free ends of 90 the spring-catches G G on their under side, and thus lift their hooked ends out of engagement with the notched upper edge of plate C. To use this device, each holder (comprising 95 two recessed plates hinged together, as described) is opened and filled with its appropriate number of cartridges, which are placed in the recesses D, with the wire guard or keeper F bearing against one side, after which the holder is closed by snapping the plates 100 together. In this position the cartridges can be carried safely, free from liability to injury

and without danger of their falling out until they are required for use. When wanted, all that is necessary is to depress the thumb-buttons 11, when the outside plate E will 5 open out, carrying the cartridges with it, which, guided by the wire keeper F, will drop into the hand held below, ready for insertion into the chambers of the revolver or magazine of the rifle. In moving the hand up again to 10 charge the rifle or revolver, plate E is again folded up upon plate C and the two are snapped together.

It is obvious that, if desired, the body of the belt A, if made of leather or other sufficiently stiff material, may be molded or stamped, so as to form the back recesses D, thereby dispensing with the back plates C. In that case the upper part of the belt above 20 the cartridge-recesses should be provided with a metal rim to engage the spring hooks or fastenings of the hinged front plate. It will also be seen that, if desired, two or more rows of these holders may be fastened upon a belt of sufficient width one above another, so as to 25 form tiers or vertical rows of holders, where it is desired to carry a large number of cartridges upon the person at one time.

Having thus described my invention, I claim

and desire to secure by Letters Patent of the United States—

1. The combination, with the belt, of the individual holders or cartridge-carriers, each comprising a hinged recessed flap adapted to open outwardly and downwardly, a correspondingly-recessed body-piece, and a spring-30 catch for locking the free end of the hinged plate to the top of the recessed body-piece, substantially as and for the purpose shown and set forth.

2. The combination of the recessed body-piece or back plate, the correspondingly-recessed front plate hinged to the lower end of the recessed back, a spring-snap or lock for closing the front plate upon the back, and the spring guard or keeper disposed between the 40 hinged front and fixed back and adapted to guide the cartridges as these slide out of their respective recesses or chambers, substantially as and for the purpose shown and set forth.

In testimony that I claim the foregoing as my 45 own I have hereunto affixed my signature in presence of two witnesses.

ANTHONY J. BLIX.
